UNITED STATES PATENT OFFICE.

CHARLES D. SMITH, OF BIRMINGHAM, ALABAMA, ASSIGNOR OF ONE-FOURTH TO KYLE
LAWSON AND ONE-FOURTH TO ALVIN M. DOUGLAS, BOTH OF BIRMINGHAM,
ALABAMA.

RAILWAY TIE OR SLEEPER.

1,032,567.

Specification of Letters Patent. Patented July 16, 1912.

Application filed February 23, 1912. Serial No. 679,389.

To all whom it may concern:

Be it known that I, CHARLES D. SMITH, citizen of the United States, residing at Birmingham, Alabama, have invented certain new and useful Improvements in Railway Ties or Sleepers, of which the following is a specification.

My invention relates to new and useful improvements in railway cross ties or sleepers, and especially to those made of reinforced concrete.

The advantages of the reinforced concrete tie over wood, especially in the matter of durability, is well known, but heretofore such concrete ties have not gone into extensive use due to certain inherent defects in their construction.

I have aimed, in the present invention, to provide a concrete cross tie in which provision will be made for slight motion in the ties while the train is passing over them, thus securing the equivalent of the slight elasticity of the wood tie.

A further object is to provide a tie made of two parts which are exact duplicates of each other, and which may be shipped detached and readily assembled, thereby greatly facilitating the handling in shipment, the great weight of the ordinary full length concrete tie being a serious drawback.

A further object is to provide a novel form of reinforcing means which also plays a part in securing the two sections of the tie together, and still another object is to provide, in connection with a tie of this character, simple and efficient means for securing the rails thereto.

With these and other objects in view, the invention consists in the novel features of construction and combination and arrangement of parts hereinafter described and particularly defined in the appended claims.

A cross tie constructed in accordance with my invention is illustrated in the accompanying drawings, in which—

Figure 1 is a plan view; Fig. 2 is a side elevation; and Figs. 3 and 4 are detail views. Fig. 5 is a view of a modified form.

Referring by reference characters to this drawing, the numerals 1 and 1^a designate the two sections of the improved cross tie, which are molded to be substantial duplicates of each other, and having abutting portions *a* and *a'*, and lower cut away portions *b* and *b'*. These two sections are de-

tachably connected together by the reinforcing rods 2 and 2^a, which are embedded in the sections in the process of molding, and are provided at their extremities with hooks and eyes 3 and 4, respectively, by which the sections are detachably connected together. They are further connected by a pin 2^b molded in and projecting from one of the sections and engaging a corresponding recess in the other section. The hooks and eyes of the two sets of rods are preferably reversely arranged, that is, on one side of the tie one rod 2 carries the hook, and the other 2^a the eye, while on the opposite side of the tie the first named rod carries the eye and the second the hook. The hinged joint formed by the hook and eye connection comes directly beneath the line of contact between the abutting portions *a* and *a'*, and this, together with the cut away portions below the joint, enables the ends of the tie to be capable of a slight upward and downward movement, or in other words, gives a slight degree of flexibility between the two parts. The rods 2 and 2^a are provided at their extremities with angularly turned ends 5 serving to anchor them firmly in the concrete. Each section is provided with a widened out portion or extension on each side, as indicated at 1^b and 1^c, respectively, to form a broad seat for the rail, these widened out portions joining the body of the tie on curving lines, as clearly shown in the plan view, thereby securing greater strength. Cross reinforcing rods are provided in this widened out portion, as indicated by the numeral 7, these cross rods being arranged in pairs with the ends turned toward each other to secure the anchoring effect, as indicated at 7^a. When desired, certain of the sections may be molded short on one side, as indicated in Fig. 5, whereby two ties may be placed close together at the rail joint, the short wings serving to engage the joint chairs, or rail joints, or plate.

In order to secure the rails to the ties, I provide each section of the tie in molding with a recess 8 which has parallel side walls and end walls which flare outwardly and downwardly, as indicated at 8^a. Within this recess I place a wooden block 9 which has parallel side walls corresponding to the side walls of the recess, and downwardly flaring end walls. The length of block at the bottom is equal to the length of the re-

cess at the top, so that the block may be easily inserted in the recess, and when lodged therein, leaves an inclined space at each end. Into this I pour a compound 5 composed of hot coal tar and sand which will harden when cooling, and which, filling in around the wood block, serves to hold the same in position. Over this wood block I place a rail supporting plate 10 provided 10 with holes for the reception of spikes, and secure the rail in place by driving the spikes 11 through the plate into the wood block.

Instead of using spikes I may use a steel 15 clamp fastening as shown on the left hand side of Figs. 1 and 2, in which plates or bars 12 are provided having upper ends 12^a designed to be bolted to opposite sides of the web of the rail, and inclined portions 12^b resting upon the base of the rail. Below 20 the said base the bars are provided with downwardly extending ends having outwardly turned hooked ends 12^c designed to hook under the cross reinforcing rods 7.

Having thus described my invention what 25 I claim is:

1. A railroad tie comprising a pair of 30 duplicate concrete sections, longitudinal rods anchored in each section, said rods projecting from the ends of said sections and provided respectively with hooks and eyes adapted for detachable connection and when holding said sections abutting against each

other, said sections having undercut portions adjacent the projecting ends of the rods permitting a downward flexing motion 35 of the outer ends of the sections, substantially as described.

2. A railroad tie comprising a pair of 40 duplicate concrete sections, longitudinal rods anchored in each section, said rods projecting from the ends of said sections and provided respectively with hooks and eyes adapted for detachable connection, said sections having abutting portions and undercut portions adjacent the projecting ends 45 of the rods, and a pin projecting from the abutting portion of the end of one section and engaging a hole in the abutting portion of the other section, substantially as described.

3. A railroad tie comprising a pair of 50 concrete sections detachably connected together, said sections having cross reinforcing rods and recesses adjacent thereto, and tie bars adapted to be bolted to opposite sides of the rail, and having hooked ends depending in said recesses and engaging said cross rods.

In testimony whereof I affix my signature in presence of two witnesses.

CHARLES D. SMITH.
